UNITED STATES PATENT OFFICE.

GEORGE CORMACK, JR., AND FREDERICK C. ZUMDAHL, OF ROCKFORD,
ILLINOIS.

GOVERNOR FOR GASOLENE-ENGINES.

No. 836,096.

Specification of Letters Patent.

Patented Nov. 20, 1906.

Application filed February 5, 1904. Serial No. 192,106.

To all whom it may concern:

Be it known that we, GEORGE CORMACK, Jr., and FREDERICK C. ZUMDAHL, citizens of the United States, residing at Rockford, in the county of Winnebago and State of Illinois, have invented certain new and useful Improvements in Governors for Gasolene-Engines, of which the following is a specification.

10 The object of this invention is to vary the speed of a gasolene-engine by a connection which varies the influence of the governor.

In the accompanying drawings, Figure 1 is an elevation of a portion of an explosive-engine, showing the relation of our improvements thereto. Fig. 2 is a side elevation of a governor and its connection with the parts of a gasolene-engine. Fig. 3 is a fragmental representation of the parts of a gasolene-engine acted upon by the governor and our improvements in connection therewith. Fig. 4 is a horizontal section on dotted line *a*, Fig. 2. Fig. 5 is an elevation of a portion of a gasolene-engine, showing the rocker-arm connection with the exhaust-valve.

25 The shaft 1 is constantly rotated, which will rotate the cam 2 and the beveled toothed wheel 3. The shaft 1 is supported at one point by the bracket 4, which has a tubular bearing 5 connected therewith. A shaft 6 is held in place by the bearing 5, its upper end supporting the cap 7 and its lower end a beveled toothed pinion 8, meshing with the teeth of the beveled toothed wheel 3. Balls 9 have a pivotal connection with the cap 7 and have arms 10 engaging a sliding sleeve 11 mounted on the shaft 6. Springs 12 connect the balls. A collar 13 has a connection with the sleeve 11, and the arm 14 of a bell-crank lever has a connection with the collar. The arm 15 of the bell-crank lever has a rod 16 pivotally connected to its free end. This bell-crank lever is pivotally supported by the bracket 17, extending from the bearing 5. 30 A roller 18 is supported by a rocker-arm 19. This rocker-arm or exhaust-valve lever is employed to open the exhaust-valve 39 of the gasolene-engine. This arm 19 has a plate 20 secured to its upper face, which is provided with a ledge 21. A lever 22 is pivoted at 23 to any stationary part of the engine, its lower end provided with a plate 24,

adapted to engage the ledge 21 of the plate 20. The upper end of this lever supports a double-ended rocking bar 25, one end provided with a horizontal opening 26 and its other end provided with an opening 27.

5 The rod 16 passes through the opening 26 and has collars 28 set either side of the bar. A rod 29 is located in the opening 27 of the 60 rocking bar 25 and has two collars 30 and 31 secured thereto, one each side of the bar. A spring 32 surrounds the rod 29 and is located between the collar 30 and bar, and a spring 33 surrounds the rod 29 and is located between the collar 31 and bar. The other end of this rod 29 has a pivotal connection with a hand-lever 34, which has a pivotal connection with a toothed segment 35. The teeth of this segment 35 are in two series 36 and 37 70 each side of the center notch 38. The latch 39 is operated by a thumb-lever, as is common in such constructions.

When the governor shifts its position under varying speeds, the lever 22 is oscillated, 75 which when the rocker-arm 19 is depressed by the projection 2 will at times engage the seat 21 and hold the rocker-arm from returning, thereby holding the exhaust-valve open, which takes place when the engine is running 80 above its normal speed; but when the engine is running below its normal speed the lever will stand free of the seat, allowing the exhaust-valve to close at each compression.

By means of the hand-lever 34 the rod 29 85 can be moved in its lengthwise direction—for instance, to the right—which will carry the spring 32 into engagement with the arm 25, thereby moving the arm and holding the lever 22 in engagement with the seat 21, 90 which will hold the exhaust-valve open and stop or slow down the speed of the engine. By moving the hand-lever to the left the spring 33 will be brought into engagement with the arm 25, which will hold the lever 22 95 free of the seat and permit an explosion at each compression, thereby increasing the speed of the engine. When the hand-lever 34 is returned to its central position, the governor will take up its work and hold the engine at its normal speed.

It will be noticed that there is some distance between the springs 32 and 33 and the bar 25. This is to allow sufficient play for

the governor to act without being interfered with by the lever 34, which remains stationary.

We claim as our invention—

- 5 1. An attachment for gasoline-engines comprising a governor, a connection between the governor and device controlling the exhaust-valve, a hand-operated rod connected with the valve-controlling device, a spring on the rod each side of said device, and a collar outside of each spring, the springs being separated sufficiently to permit a movement of the device without engaging them.
- 10 2. An attachment for gasoline-engines,

comprising a governor, a connection between 15 the governor and devices controlling the exhaust-valve, a hand-lever, a rod connecting the hand-lever and exhaust-valve-controlling device, a spring on the rod each side of said device and a collar outside of each spring, the 20 springs separated sufficiently to permit a movement of the device without engaging them.

GEORGE CORMACK, JR.
FREDERICK C. ZUMDAHL.
